UNITED STATES PATENT OFFICE.

CHARLES MORRIS HOLMES, OF JACKSONVILLE, FLORIDA.

DEVICE FOR COUPLING A TELEGRAPH TRANSMITTER AND SENDING-KEY.

1,232,548.

Specification of Letters Patent. Patented July 10, 1917.

Application filed March 31, 1916. Serial No. 87,866.

To all whom it may concern:

Be it known that I, CHARLES M. HOLMES, a citizen of the United States, and a resident of Jacksonville, in the county of Duval and State of Florida, have invented a new and Improved Device for Coupling a Telegraph Transmitter and Sending-Key, of which the following is a full, clear, and exact description.

10 This invention relates to telegraph apparatus and has to deal more particularly with a device for coupling a transmitter with a standard telegraph key.

The invention has for its general objects 15 to provide a device of the character referred to which is reliable and efficient in use, comparatively simple and inexpensive to manufacture, and so designed as to facilitate the connecting of the transmitter with the sending key.

A more specific object of the invention is to improve a telegraph key for permitting a transmitter to be connected by a cord with the key, the coupling means including a split 25 metal socket on the key with its parts respectively connected with the terminals of the key, and a split plug insertible in the socket and connected with the conductors of the cord, whereby the terminals of the 30 transmitter can be electrically connected in a reliable and positive manner with the sending key.

With such objects in view, and others which will appear as the description proceeds, the invention comprises various novel features of construction and arrangement of parts which will be set forth with particularity in the following description and claims appended hereto.

40 In the accompanying drawing, which illustrates one embodiment of the invention and wherein similar characters of reference indicate corresponding parts in all the views,

45 Figure 1 is a plan view of a key, showing the coupling device in section on the line 1-1, Fig. 2;

Fig. 2 is a side view of the key and coupling device, one of the pivot bearings of 50 the key being in section on the line 2-2, Fig. 1;

Fig. 3 is a vertical section on the line 3-3,

Fig. 2;

55 Fig. 4 is a perspective view of the socket removed;

Fig. 5 is a detail sectional view on the line 5-5, Fig. 3.

Fig. 6 is a sectional view of the split plug; and

Fig. 7 is a sectional view on the line 7-7, 60 Fig. 6.

Referring to the drawing, A designates an ordinary sending key to which is applied the coupling device B, which latter may be in the form of an attachment, as shown; or 65 it may be a permanent part of the framework of the key. The key comprises the usual parts consisting of the frame or base 1; posts 2 that support the pivot screws 3, and jam nuts 4; the key lever 5 fulcrumed 70 on the pivot screws and having a contact 6 adapted to engage the contact 7 carried by but insulated from the frame 1; binding posts or terminals 8 and 9, the first of which is insulated from the frame 1 and electrically connected with the plate 10 which is 75 electrically connected with the contact 7 and has a spring switch member 11 with which engages the cut-out lever 12 fulcrumed at 13 on the frame 1, and on the main lever 5 is 80 the usual stop set screw 14.

The coupling device in the present instance is shown as an attachment and is adapted to be fitted to the pivot supporting posts 2 of the key. It comprises a metal 85 socket 15 split axially into two parts 16 and 17 which are mounted on a block of insulation 18 and thereby insulated from each other. The socket parts are fastened to a bridge-piece 19 which bears on top of the 90 posts 2, and fastened thereto by any suitable manner, as for instance, angle clips 20 which are secured to the ends of the bridge-piece by screws 21 and which have slots 22 in their depending arms which straddle the 95 pivot screw 3, and the jam nuts 4 clamp the clips against the outer faces of the pivot posts 2. By this manner a good electrical connection is obtained between the half 16 of the socket and the frame of the key. The 100 half 16 of the socket is fastened to the bridge by screws 23 which electrically connect these parts. The half 17 is connected to the bridge by screws 24 which are separated by insulation 25 from the bridge piece, as 105 clearly shown in Fig. 5. One of these screws 24 serves as a binding post for fastening a wire 26 with the insulated binding post 8 of the key. It will thus be seen that the section 16 of the socket 15 is grounded 110

on the frame of the key, and hence is connected with the circuit wire 27, and the section 17 of the socket is connected with the other circuit wire 28 through the conductor 26 and binding post 8. The plug 29, which is insertible in the socket 15, is made in two parts 30 and 31 separated by a strip 32 of insulation which projects beyond opposite edges of the parts 30 and 31, as shown in Fig. 7, so as to engage between the sections 16 and 17, thus preventing the insertion of the plug, except in proper position. The parts 30 and 31 are fastened in a sleeve or carrier 33 and they are connected respectively with the wires 34 and 35 of the cord 36, which leads to the transmitter.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. The combination of a telegraph key having the usual insulated and uninsulated terminals, with a device for coupling a transmitter with the key, said device comprising a two-part socket, the parts of which are insulated from each other and normally electrically disconnected, one part being connected with the uninsulated terminal of the key and the other part connected with the insulated terminal, a plug having two insulated parts insertible in the socket to respectively engage the parts thereof, a conductor cord having its wires connected respectively with the parts of the plug, and means for clamping the device to the frame of a key.

2. The combination of a telegraph key having the usual insulated and uninsulated terminals, with an attachment for coupling the key with a transmitter, said attachment comprising a support adapted to be clamped to the frame of the key, a split socket having rigid parts insulated from each other and normally electrically separated, one part being grounded on the support and thereby electrically connected with the uninsulated terminal, a conductor separate from the key connecting the other part of the socket with the insulated terminal of the key, a two-part plug insertible in the socket, and conductors

tors connected respectively with the parts of the plug and adapted to be connected with the transmitter.

3. The combination of a telegraph key including a frame having key lever supporting posts and insulated and uninsulated terminals, with a device for coupling the key with a transmitter, said device comprising a bridge-piece attached to and grounded on the posts, a split socket having its parts fastened to the bridge-piece and one being insulated from the other and from the bridge-piece, a conductor connecting the insulated part of the socket with the insulated terminal, and a two-part plug insertible in the socket and having means for preventing the plug from being inserted except in proper position.

4. The combination of a telegraph key including a frame having insulated and uninsulated terminals, with a coupling attachment for connecting the key with a transmitter, said attachment forming a unitary device separable from the key and comprising a socket split longitudinally into two parts insulated from each other and one part being insulated from the frame, a conductor separate from and connecting the insulated part of the socket with the insulated terminal, a plug split longitudinally into two parts and having a piece of insulation between the parts, which insulation is adapted to engage into the split of the socket to limit the insertion of the plug in the proper manner, and conductors connected with the respective parts of the plug.

5. The combination of a telegraph key including a frame having a lever provided with a contact, a contact with which the contact on the lever is adapted to engage, insulated and uninsulated binding posts on the frame, and switch means for connecting the frame with the insulated contact, with a device for coupling the key with a transmitter, said device comprising spaced socket members insulated from each other and one member being grounded on the frame and the other insulated therefrom, a conductor connecting the insulated binding post with the insulated socket member, a plug composed of insulated parts adapted to engage the respective socket members, and conductors connected respectively with the parts of the plug.

In testimony whereof I have signed my name to this specification in the presence of two subscribing witnesses.

CHARLES MORRIS HOLMES.
